CLAIM

The ornamental design for a clip for a pager, as shown and described.

DESCRIPTION

FIG. 1 is a top plan view of a clip for a pager showing our new design;

FIG. 2 is a left side elevational view thereof;

FIG. 3 is a right side elevational view thereof;

FIG. 4 is a bottom elevational view thereof;

FIG. 5 is a rear elevational view thereof;

FIG. 6 is a front elevational view thereof; and,

FIG. 7 is a top rear left side perspective view of the clip for a pager, wherein the broken lines showing a pager environment are for illustrative purposes only and form no part of the claimed design.

*FIG. 1**FIG. 4**FIG. 2**FIG. 3**FIG. 5**FIG. 6*

FIG. 7
